GARMENT GRIP OR THE LIKE

Harold F. Burnham, Highland Park, N. J., assignor to Johnson & Johnson, a corporation of New Jersey

Application April 26, 1950, Serial No. 9,501

Term of patent 14 years

(Cl. D17—9)

To all whom it may concern:

Be it known that I, Harold F. Burnham, a citizen of the United States, residing at Highland Park, in the county of Middlesex, State of New Jersey, have invented a new, original, and ornamental Design for a Garment Grip or the Like, of which the following is a specification, reference being had to the accompanying drawing, forming a part thereof in which:

Fig. 1 is a plan view of a garment grip or the like showing my new design; and

Fig. 2 is a side elevational view.

I claim:

The ornamental design for a garment grip or the like, substantially as shown.

HAROLD F. BURNHAM.
